UNITED STATES PATENT OFFICE.

FRANCIS WALTER GUIBERT, OF DETROIT, MICHIGAN.

INTERNAL-COMBUSTION ENGINE.

1,391,106.

Specification of Letters Patent. Patented Sept. 20, 1921.

Application filed January 25, 1919. Serial No. 272,996.

To all whom it may concern:

Be it known that I, FRANCIS WALTER GUIBERT, a citizen of the United States of America, residing at Detroit, in the county of Wayne and State of Michigan, have invented certain new and useful Improvements in Internal-Combustion Engines, of which the following is a specification, reference being had therein to the accompanying drawings.

10 The invention relates to internal combustion engines and has for its object the prevention of accumulation of carbon. To this end the invention consists in the means employed as hereinafter set forth.

15 The drawing represents diagrammatically a portion of an internal combustion engine to which my improvement is applied.

In the operation of internal combustion engines with hydrocarbon fuel great difficulty is experienced in the depositing of carbon on the walls of the clearance spaces and also on the valves and valve-seats. Usually the surfaces on which the carbon is deposited are formed of iron or of an alloy containing a large ferrous constituent. Thus when such a metal is heated its strong affinity for carbon will cause the breaking down of hydrocarbon vapors in contact therewith, leaving the solid carbon deposit. Further-

30 more, after an initial deposit of carbon upon the surface more carbon will be accumulated thereby, soon resulting in pre-ignition, abrasion of the valves and seats and other objections incident to the presence of carbon.

35 The principle underlying the present invention is to prevent the initial deposit of carbon and consequently to avoid accumulation of the same. This is accomplished by forming the exposed surfaces of material 40 which has no affinity or less affinity for carbon than ferrous metal; one such substance is copper or alloys containing a relatively

large copper constituent; but it is obvious that there may be other materials equally well adapted for the purpose.

45 It is immaterial to the invention whether the structure having the exposed surface is formed in its entirety of the selected material or whether there is simply a surface coating of such material. In either case the exposed surface will have little or no affinity 50 for the carbon, and thus breaking down of the hydrocarbon vapors is avoided. The protecting material may also be applied either to the entire exposed surface or to 55 only portions thereof which are most liable to receive carbon deposits.

In the drawing I have represented diagrammatically an internal combustion engine, in which A is the cylinder, B the clearance space or explosion chamber, C, the piston, and D the valves. The walls of the clearance space B are coated with the protecting material, as indicated by the heavy line E, which may be deposited by any suitable means, such as electroplating, spraying, etc. In the same manner the exposed end of the piston and exposed surfaces of the valves may be similarly coated, as indicated at F and G.

70 What I claim as my invention is:

1. In an internal combustion engine, a wall exposed to carbon gases or vapors having an exposed lining formed of material with a relatively large copper content.

2. In an internal combustion engine, the combination with an explosion chamber including a cylinder wall and a piston and valve, of linings upon said wall, piston and valve, exposed to the carbon gases or vapors and formed of material with a relatively large copper content.

75 80 In testimony whereof I affix my signature.

FRANCIS WALTER GUIBERT.
